UNITED STATES PATENT OFFICE.

EDUARD SCHMACHTL, OF OBER-WALTERSDORF, AUSTRIA-HUNGARY.

SPOOL-CARRIER FOR BRAIDING, LACE-MAKING, AND LIKE MACHINES.

1,149,088.

Specification of Letters Patent.

Patented Aug. 3, 1915.

Application filed June 30, 1913, Serial No. 776,613. Renewed January 5, 1915. Serial No. 669.

To all whom it may concern:

Be it known that I, EDUARD SCHMACHTL, a subject of the Emperor of Austria-Hungary, and resident at Ober-Waltersdorf, Austria-Hungary, have invented certain new and useful Improvements in or Relating to 5 Spool-Carriers for Braiding, Lace-Making, and like Machines.

The invention has reference to improvements in or relating to spool-carriers for braiding, lace-making and like machines and it consists in a spool carrier the characteristic feature of which, as compared with the known carriers, is that the horizontal 10 spool spindle is carried by a slide which is guided so, that it can move up and down upon the bobbin stand and which acts as a weight upon the spool to produce the necessary tension on the thread.

20 I have illustrated my invention in the accompanying drawing in which,

Figure 1 shows my improved spool carrier in side elevation and partly in section, and Fig. 2 is a plan view of Fig. 1.

25 The table or carriage (not shown) of the braiding or like machine engages in the space 1 between the supporting flanges 2, and the upper flange 2 carries the bobbin stand consisting of two vertical bars 3 and 4. A slide 5 which carries a horizontal 30 spindle 6 on which the spool is placed is mounted slidably upon the bar 3, and one of the flanges 7 of the spool is formed with ratchet teeth. A pawl 9 which is pivotally 35 mounted on the slide 5 is pressed by a spring 10 toward the teeth in the flange 7 and is constantly engaged in a vertical slot 11 in the shorter bar 4. The space between the top of the bar 4 and the thread guide 12 at 40 the upper end of the bobbin stand is left free for the purpose of enabling the spool 8 to be readily removed from the spindle 6 and a fresh spool to be placed in position when the spool carrier is raised. The 45

thread guide arm 14 is curved, about as shown in the drawing, so that it lies at one side of the path of the slide 5, so that the upper end of the slide can project through the opening formed by the bend 15. Due to 50 this arrangement the slide 5 can be readily removed from the rail 3 when the spool 8 is removed from its spindle 6 and the pawl or lever 9 is disengaged from the slit 11.

A further feature of the invention consists in that the slide 5 has a projection 16 which extends into the path of the lever 9

and limits the downward movement of the said lever. The lengthening or shortening of the thread which takes place during the working of the machine is compensated for 60 by the slide 5 moving downward or upward upon the rail 3, so that the tension on the thread always remains the same. A subsequent delivery of the thread is permitted, when the spool 8 is raised sufficiently far 65 together with the slide 5 and the hinge of the lever 9, when the free end of the latter is brought into contact with the upper edge of the slot 11, whereupon the toothed flange 7 is released from the said lever and the 70 spool rotates one tooth farther, allowing a corresponding length of the thread 13 to be drawn off, this procedure being repeated as soon as the thread given off has been worked into the fabric which is being produced or 75 operated on.

When a number of spools are employed and a single thread breaks, the other threads may easily become entangled and prevented from running off the spool. Thereby the 80 spool would, correspondingly to the working-in of the threads, be raised farther and the result would be that defective work might be produced if the extent of movement of the spool were not limited by the 85 stop 16, as shown in the drawing, so that all the threads break without fail at the right moment, whereupon the slide 5 falls down and its laterally projecting pin 17 then brings about in the known manner the automatic stopping of the machine. The weighting of the thread or the necessary 90 tension on same may be varied, for example, by hanging suitable weights on the slide 5. Such weights are preferably adapted to slide upon the rail 3 and to engage the 95 said rail similarly to the slide 5.

I claim:

1. In a spool carrier, the combination with a spool having a ratchet, of a vertical bobbin stand therefor, a spindle for said spool, a plate secured to said spindle, ears on said plate adapted to engage the bobbin stand whereby the spool will be slidably mounted thereon to produce the necessary thread tension by the weight of the spool, and a pawl on the bobbin stand to engage the ratchet on the spool. 100

2. In a spool carrier, the combination with a spool supporting member, of a spool mounted thereon, said spool having a ratchet, a relatively shorter member oppo- 110

site the spool support, said shorter member extending to the base of the spool when in filling position, whereby a span is formed for the insertion or removal of the spool, and a pawl mounted on the spool supporting member to engage the ratchet, said pawl being limited in its movement in one direction by the shorter member.

3. In a spool carrier, the combination with 10 an upright, of a member slidably mounted thereon, a spool on said slideable member, a thread guide on said upright, an arm extending rearwardly from the upright and reversely curved to permit the removal of 15 the slideable member from the upright, and means mounted on the slide to engage the spool when the latter is lowered by the slide.

Copies of this patent may be obtained for five cents each, by addressing the "Commissioner of Patents, Washington, D. C."

4. In a spool carrier, the combination with a slidably mounted spool having a ratchet, of means for limiting the upward movement 20 of said spool, said means comprising a slide, a shoulder on said slide, a pivoted member on the said shoulder to engage the ratchet, an upright provided with a slot adapted to be engaged by said pivoted member, a 25 spring bearing on said member to force the same into the slot, and means for pivotally mounting said spring.

In testimony whereof I have set hereunto my hand in presence of two witnesses.

EDUARD SCHMACHTL.
